UNITED STATES PATENT OFFICE.

WILLIAM P. ESPY, OF SPRINGFIELD, OHIO.

FLUID-MOTOR.

1,113,155.

Specification of Letters Patent.

Patented Oct. 6, 1914.

Application filed July 9, 1913. Serial No. 778,153.

To all whom it may concern:

Be it known that I, WILLIAM P. ESPY, a citizen of the United States, residing at Springfield, in the county of Clark and State 5 of Ohio, have invented certain new and useful Improvements in Fluid-Motors, of which the following is a specification, reference being had therein to the accompanying drawing.

10 This invention relates to fluid motors and the object of the invention is to provide a motor in which the valves can be reversed without the use of springs; and in which the valve-shifting device will be simple in 15 its construction and operation, and will require no delicate adjustments or fine divisions of pressure, and which will be positive in its action.

To this end it is also an object of the invention to provide a valve-shifting device which will be acted upon by the direct pressure of the incoming fluid without the necessity of confining the fluid in any manner.

In the accompanying drawings, Figure 1 25 is a horizontal sectional view of a motor embodying my invention taken through the inlet valve chamber; and Fig. 2 is a vertical, sectional view taken on the line xx of Fig. 1.

In these drawings I have illustrated one 30 embodiment of my invention and have shown the same as applied to an oscillating motor of a well known construction. This motor comprises a body portion consisting of a cylinder 1 and cylinder heads 2 and 3.

35 Centrally mounted within the cylinder is a motor shaft 4 which is preferably journaled in the cylinder heads and provided with suitable stuffing boxes. This motor shaft carries a wing piston 5 which operates in 40 the cylinder in the usual manner and cooperates with an abutment or partition 6 to divide the cylinder into two compartments. In this type of motor the fluid is sometimes admitted through the abutment 45 or partition 6 and sometimes through the motor shaft and piston. In the present instance I have utilized the former method and have provided the abutment with two valve chambers, the lowermost of which, as 50 shown at 7, constitutes the exhaust valve chamber, communicates with the exhaust pipe 8 and has mounted therein a double puppet exhaust valve 9 which controls the communication of the exhaust chamber with

the two compartments of the cylinder so as 55 to exhaust the water alternately on opposite sides of the piston. The upper valve chamber formed in the abutment, as indicated at 10, comprises an inlet chamber and communicates with the interior of the cylinder 60 on both sides of the piston by the usual ports which are controlled by the valve members 11 and 12 of a double puppet valve. This chamber communicates by means of a port 13 with an inlet or supply pipe 14. The inlet port 13, in the present form of motor, is formed in the wall of the cylinder instead of in one of the cylinder heads, as is the more common practice in this type of motor. This arrangement, however, is an optional one and may be varied at will. The initial movement is imparted to the valves 65 to unseat them by means of projections or fingers 15 secured to the opposite sides of the piston 5 and arranged to engage the adjacent ends of the valves as the piston approaches the limit of its movement in either direction. As is well known, if no means are provided for imparting further movement, to the valves after they have been 70 unseated, by the action of the piston, they will become balanced because when they reach what is known as their "dead-center" 75 position water will escape equally to and from both sides of the piston and, consequently, there will be no further movement of the piston to carry the valve across its dead-center position.

The dead center position is usually the central position in which the ports of both 90 valve members will be open to exactly the same extent, but under varying pressures and load the exact point at which the valve will balance sometimes varies and the term "central" or "dead-center" position as employed herein means the point at which the valve will balance. As is also well known the springs which are commonly used to impart further movement to the valves to carry them across their dead-center positions are open to numerous objections, such as the tendency of the springs to crystallize 95 and break and the difficulty of adapting a single spring to different water pressures. Various attempts have been made to do 100 away with the springs and produce a valve-shifting device which will be actuated by water pressure, but in many, if not all cases,

the shifting device was of such a character that it required delicate adjustments or fine divisions of water pressure in order to render the same operative.

Inasmuch as these motors are commonly applied to washing machines and are operated by women and others absolutely unskilled in mechanics it is essential that the valve-shifting mechanism shall be of such a simple, positive character that it cannot be easily disarranged or rendered inoperative. In other words, it must be "fool proof." In order to produce such a valve shifting means I have provided a valve-shifting device so mounted that it will normally lie out of the path of the fluid entering the valve chamber, that is, it will in no way interfere with the direct passage of the fluid to the open port leading to the interior 20 of the cylinder. This valve shifting device is so connected with the inlet valve that the initial movement of the inlet valve, to unseat the same, will move the valve-shifting device into the path of the incoming fluid 25 and the movement of the valve-shifting device will be such that by the time the inlet valve has reached its dead-center position the valve-shifting device will have been moved into the path of the fluid a distance 30 sufficient to divert the greater portion of the fluid to the rear of the shifting device. Inasmuch as the fluid is escaping through both ports in equal amounts the additional quantity of water passing to the rear of the 35 device will exert a pressure thereon which will tend to continue the movement of the valve-shifting device and the valve, thus carrying the latter across its dead-center position. It is immaterial whether or not 40 the valve-shifting device completes the movement of the valve, as after it has once crossed the dead-center position the action of the water will move it to its seat. This result can be accomplished in various manners, but in the particular form of the invention here illustrated, the valve-shifting device comprises a blade or vane 16 mounted 45 within the inlet valve chamber, on an axis extending transversely to the inlet valve and on that side of the inlet valve opposite the port leading from the supply pipe to the valve chamber. This vane is of such a size 50 as to substantially form a vertical partition within the chamber and is so connected with the inlet valve as to move with it. As here shown, the inlet valve has a reduced central portion 17 and the vane 16 has a slot, as 55 shown at 18, to slip over the reduced portion. Thus, the vane will lie within the 60 groove formed by the reduced portion between the opposite end portions of the valve and will be caused to move about its axis in the same direction that the valve is moved. The width of the groove is sufficiently 65 greater than the thickness of the

vane to allow for the movement of the vane about its axis. When one of the valve members is seated that end of the vane adjacent the inlet port 13 will lie close to or beyond the edge of the port so that it will be out of the path of the incoming fluid and will not interfere with the passage of the fluid from the port 13 to the port leading to the interior of the cylinder. That face of the vane adjacent to the port will, in a sense, 70 form one wall of the inlet valve chamber and the pressure of the water against this wall will tend to retain the valves in their positions. When the initial movement is imparted to the valve by one of the arms 75 15 on the piston 5 the vane will likewise be moved and, inasmuch as the vane is mounted on an axis remote from the valve, the free edge of the vane will move faster than the valve moves. As a result this difference in 80 the movements of the valve and the vane the edge of the vane will be carried past the center of the port 13 by the time that the inlet valve reaches its balanced or central position. The larger portion of the water 85 will, therefore, enter the valve chamber in the rear of the vane and a greater pressure will be exerted upon this side of the vane than is exerted on the forward side thereof and this pressure will tend to continue the 90 movement of the vane and the valve. It is not necessary to the proper action of the valves that the exhaust valve be connected with the inlet valve and I have not shown such a connection, but it will be understood 95 that such a connection may be made in the usual manner if desired. 100

The operation of the valve-shifting device will be clearly understood from the foregoing description and it will be apparent that the device is very simple, both in its construction and operation; that it can be manufactured at a very low cost; that it will require little machining and no fine adjustments; and that its movement and operation 110 will be positive, thus eliminating all uncertainty of the operation of the valve.

While I have shown and described the invention as applied to a double puppet valve oscillating motor it will be understood that 115 this type of motor is used for the purpose of illustration only and that the invention can be applied to motors of various kinds and in connection with valves of various types, and further, that the details of construction herein shown and described are also chosen for the purpose of illustration and I do not wish to be limited to the construction shown and described, for obvious modifications will occur to a person skilled 120 in the art.

Having thus fully described my invention, what I claim as new and desire to secure by Letters Patent, is:—

1. In a fluid motor, the combination, with 130

an inlet valve, of a valve shifting device having a part movable into different positions to subject different sides thereof to the action of the fluid, and a connection between said valve and said valve shifting device, whereby the initial movement of said valve in either direction will cause said part of said valve-shifting device to be moved into a position to subject one side of it to the action of the fluid, and the action of the fluid on said valve-shifting device will cause a further movement of said valve.

2. In a motor, the combination, with a cylinder, a piston mounted therein, one of said parts having a valve chamber communicating with the interior of said cylinder on both sides of said piston and having an inlet port, and connected valve members to control the communication between said valve chamber and said cylinder, of a valve-shifting device mounted in said valve chamber and arranged normally out of the path of the fluid entering said chamber, and a connection between said valve-shifting device and said valve members to cause said valve-shifting device to be moved into the path of the incoming fluid by the initial movement of said valve members, whereby the action of said fluid will cause a further movement of said valve members.

3. In a motor, the combination, with a cylinder, a piston mounted therein, one of said parts having a valve chamber communicating with the interior of said cylinder on both sides of said piston and having an inlet port, and connected valve members to control the communication between said valve chamber and said cylinder, of a vane arranged within said valve chamber and having one edge adjacent to said inlet port, means whereby the movement of said valve will cause said vane to move at a greater speed than that at which said valve moves and whereby the movement of said vane will impart further movement to said valve.

4. In a motor, the combination, with a cylinder, a piston mounted therein, one of said parts having a valve chamber communicating with the interior of said cylinder on both sides of said piston and having an inlet port, and a valve to control the communication between said valve chamber and said cylinder, of a vane pivotally mounted in said valve chamber on that side of said valve opposite said inlet port and having its free edge arranged adjacent to said inlet port, and a connection between said vane and said valve, whereby any movement imparted to one member will impart movement to the other member.

5. In a motor, the combination, with a part having a valve chamber, an inlet port leading to said valve chamber, two ports to permit the escape of fluid from said valve chamber, and valve members to control the

flow of fluid through said last-mentioned ports, of a valve-shifting device pivotally mounted in said chamber and having one edge arranged adjacent to said inlet port, and a connection between said valve-shifting device and said valve members, whereby the movement of said valve members will impart movement to said valve-shifting device and the movement of said valve-shifting device will impart movement to said valve members.

6. In a motor, the combination, with a part having a valve chamber, an inlet port leading to said valve chamber, two ports to permit the escape of fluid from said valve chamber, and connected valve members to control the flow of fluid through said last-mentioned ports, of a valve-shifting device pivotally mounted in said valve chamber at a point remote from said inlet port and having one edge arranged adjacent to said inlet port, said valve-shifting device being connected at a point between its axis and the free edge thereof with said valve members.

7. In a motor, the combination, with a part having a valve chamber, an inlet port leading to said valve chamber, two ports to permit the escape of fluid from said valve chamber, and connected valve members to control the flow of fluid through said last-mentioned parts, of a vane pivotally mounted in said valve chamber and having its free edge arranged to move across said inlet port, and a connection between said vane and said valve members whereby the initial movement of said valve members will impart movement to said vane and cause the latter to be moved beyond the center of said inlet port before said valve members have reached their central positions.

8. In a motor, the combination, with a casing having a valve chamber provided with an inlet port and ports to permit the passage of fluid therefrom, and a valve to control the flow of fluid through said last-mentioned ports, of a vane pivotally mounted in said valve chamber on that side of said valve opposite said inlet port, and a connection between said valve and said vane.

9. In a motor, the combination, with a casing having a valve chamber provided with an inlet port and ports to permit the passage of fluid therefrom, and a valve to control the flow of fluid through said last-mentioned ports and having an annular groove, of a vane pivotally mounted in said valve chamber on that side of said valve opposite said inlet port and having a part adapted to enter the groove in said valve.

10. In a motor, the combination, with a casing having a chamber provided with an inlet port, ports to permit the passage of fluid therefrom, and a valve to control the flow of fluid through said last-mentioned ports, of a vane pivotally mounted in said

chamber, and a connection between said valve and said vane.

11. In a motor, the combination, with a casing having a chamber provided with an inlet port, ports to permit the passage of fluid therefrom, and a valve to control the flow of fluid through said last-mentioned ports, of a vane movably mounted in said

chamber, and a connection between said valve and said vane.

In testimony whereof, I affix my signature in presence of two witnesses.
